FIG. I

8

FIG. 3

FIG. 4

INVENTOR

Russell Hoopes

By John W. Nichols attorney

UNITED STATES PATENT OFFICE.

RUSSELL HOOPES, OF WEST CHESTER, PENNSYLVANIA.

WHEEL.

1,310,189.

Specification of Letters Patent. Patented July 15, 1919.

Application filed April 2, 1918. Serial No 226,184.

To all whom it may concern:

Be it known that I, RUSSELL HOOPES, a citizen of the United States, and resident of West Chester, county of Chester, and State 5 of Pennsylvania, have invented an Improvement in Wheels, of which the following is a specification.

The object of my invention is to provide a construction of wheel which may be adapted to commercial motor wagons or to military uses, such as for wheels of artillery, and having strength and durability coupled with special adaptability for speedy and 10 easy repairs, when required because of broken spokes.

It frequently happens at the battle front, that wheels of guns and vehicles of all kinds are injured by shell fire, rendering the gun or vehicle inoperative when otherwise uninjured; and it is to remedy this condition, that the special construction embodying my invention, is directed. The wheel is so constructed that the outer ends of the spokes seat in metal sockets provided upon the 20 inner surface of a metallic or other felly or rim so as to be held against radial spreading while the hub ends of the spokes are tapered and spaced equidistant apart by keys driven in between them, said keys being 25 preferably without material taper, the said several hub portions forming an annular disk which is adapted to be clamped between the metallic flange portions of the usual axle bearings. After moving the 30 broken wheel from the metallic hub flanges, the keys upon opposite sides of the broken spoke are driven out and the injured spoke removed and replaced, after which, the new keys are driven in to position the spokes; 35 and finally, the metallic hub flanges are again secured in place; all of which may be accomplished in the open field and in a short space of time.

My invention also consists of improvements hereinafter described whereby the above objects and results are attained, said improvements comprising certain organization and combination of parts which are fully described hereinafter and more particularly defined in the claims.

Referring to the drawings: Figure 1 is a side view of one-half a wheel embodying my invention, a portion being in section for more clearly illustrating the outer support 55 for the spokes; Fig. 2, is cross sectional view of my improved wheel; Fig. 3 is a sec-

tional view of one of the spoke sockets on a larger scale; and Fig. 4 is a perspective view of one of the wooden keys.

2 are the spokes and are preferably of uniform thickness in the plane of the wheel, the outer ends 4 being circular or oval in cross section, whereas the hub end 3 is made flat on the sides and with tapered flat surfaces 3^a perpendicular to the plane of the wheel and also having their length arranged more or less radially. In transverse section, the spoke has parallel sides at the hub end 3 and may be somewhat tapered to the outer or socket end 4 (Fig. 2). It will be observed that the tapered surfaces 3^a do not have their planes pass through the axis of wheel, but are so shaped that adjacent tapered surfaces of adjacent spokes are substantially parallel, as will be understood by reference to Fig. 1. These tapered ends of the spokes are spaced apart uniformly and are tightly positioned by the spacing and locking keys 5 which are preferably of hard wood and of substantially uniform cross section along the radial direction, as will be more fully understood by reference to Figs. 1 and 4. The spokes 2 are desirably somewhat wider at the hub ends 3 than at the outer or socket ends 4 (Fig. 2), but it will be noted that the radial sides in the plane of the wheel terminate at the outer ends of the tapered portions 3^a and there are therefore no flaring or curved portions to split off as provided in spokes as usually constructed. By reason of this construction, the inward radial thrust along the spokes is directed immediately upon the tapered portions 3^a as they are within the normal width of the spoke bodies. In other words, the maximum width of the taper portion 3 of the spokes is approximately the normal width of the spoke body 2, so that there is a maximum spoke strength right down to the hub.

The rim 7 is desirably of rolled channel iron bent into a ring and welded, or formed of cast metal, as preferred. It may be strengthened by the inwardly directed flanges 8. The inner surface of the rim receives the ends 4 of the spokes as at 13 and, as has been explained, these ends are of large cross section and therefore excellently adapted to receive the hammer blows upon the rim when the wheel is in action on rough roads. As the wooden ends of the spokes are not received in sockets in the rim itself,

I provide the inner circumferential surface of the rim with socket castings or forgings 9 which are relatively shallow in radial direction, but with flanges at 14 and by which 5 they are riveted, at 11, to the rim 7. These sockets 9 have an internal diameter 10, which is smaller than the normal diameter of the end 4 of the spoke and the entrance to the socket is tapered as at 12, Fig. 3. 10 When the end 4 of the spoke is driven or forced into the socket opening 10 the tapered entrance 12 thereof compresses the wood and makes a very tight fit.

In assembling the wheel structure, the 15 spokes are all forced or driven into their respective sockets and brought into the same plane and thereafter the keys 5 are inserted and driven or pressed home tightly. The sockets 9 on the continuous metal rim receive the outward thrust of the spokes when 20 the keys 5 are driven radially outward and prevent relative displacement of the spokes during assembling; said sockets are, furthermore, the immediate means for positioning the tapered ends of the spokes in proper radial alinement. If desired, the keys 5 when being driven into position may be glued in place to maintain the assembled relation during shipment, though I have not 25 found it necessary to employ glue as the spokes and keys are sufficiently retained in firm relative positions, by friction especially because of the very small taper employed in said keys and in use, the clamping action of 30 the usual metal flanges of the axle hub and box positively holds the hub portions composed of said spokes and keys, but said axle hub and box however forming no portion of my invention. The use of glue is not pre- 35 cluded but on the other hand is not considered necessary, nor even of material advantage except so far as it may act as a filler in hardening the wood surface in contact under 40 compression. The disadvantage of the use 45 of glue is in not permitting repairs to be so easily made as in case where no glue is employed. When the hub spokes and keys are in final position the inner aperture 6 may be turned or reamed out to make the hole true 50 to insure a close fit to the metal axle box.

Referring to the socket castings 9, it will be noted that the flanges 14 thereof are curved to fit the inner curvature of rim, with the object of making a strong connection 55 and also one which is easily made watertight to protect the ends of the wooden spokes. It will also be seen that the shallowness of the sockets 10 enables the spokes 2 to be inserted and easily forced into place. The 60 space between the tapered ends of the spokes will permit all of the spokes to be placed in

position relatively to the sockets and then, by use of suitable expanding mandrel be simultaneously forced radially outward and firmly into their respective sockets until 65 their ends rest against the rim, as shown.

While the rim and sockets are separate and riveted together, they may be formed integral when cast steel is used for the rim and I therefore do not confine myself in this 70 respect. It will also be understood that while no tapers to the keys 5 are required, nevertheless a very slight taper may be employed if desired.

The rim 7 may run directly upon the 75 ground or may be provided with any suitable rubber or other tire or shoe portion, as preferred, it being immaterial to my invention as to what nature of tread portion may be employed. 80

It will now be apparent that I have devised a novel and useful construction which embodies the features of advantage enumerated as desirable, and while I have in the present instance shown and described the 85 preferred embodiment thereof which has been found in practice to give satisfactory and reliable results, it is to be understood that I do not restrict myself to the details, as the same are susceptible of modification 90 in various particulars without departing from the spirit or scope of the invention.

Having now described my invention, what I claim as new and desire to secure by Letters Patent, is:

1. In a wheel, a rim, combined with spokes fitted to the rim and having their hub ends tapered and arranged in a circle in the plane of the wheel, the adjacent tapered surfaces of adjacent spokes being approximately parallel, and keys of approximately the shape of the space between the tapered spoke ends driven radially outward between the said tapered surfaces of the adjacent spokes to position them and make a rigid hub body at 105 the inner ends of the spokes.

2. In a wheel, a rim, combined with spokes fitted thereto and having their hub ends tapered and arranged in a circle in the plane of the wheel and the adjacent tapered surfaces considerably separated, and with a width of separation at the inner hub opening equal to the maximum separation of the tapered spoke ends, and keys inserted between the tapered surfaces of the adjacent 115 spokes, a portion of said keys driven radially outward to position the spokes and make a rigid hub body.

In testimony of which invention, I hereunto set my hand.

RUSSELL HOOPES.
